ENCLOSED ARC DEVICE

Royal F. Strickland and Harold D. Blake, Cleveland Heights, and Stuart McLean, South Euclid, Ohio, assignors to General Electric Company, a corporation of New York

Application May 19, 1931, Serial No. 538,530

8 Claims. (Cl. 176—1)

Our invention relates to arc lamps of the type comprising refractory electrodes sealed in a bulb of glass or similar material containing inert gas or vapor, and more particularly to lamps of the concentrated arc type disclosed in Strickland application Serial No. 301,645, filed August 23, 1928, Serial No. 407,817, filed November 18, 1929, and Serial No. 518,146, filed February 25, 1931, which comprise a filament in multiple with the gap between the electrodes which serves as a means for starting the arc. The present invention is an improvement on the lamps disclosed in said applications and resides in the construction and arrangement of the aforesaid filament and electrodes.

In this class of lamp when the current is turned on, the filament first lights up. Inasmuch as the lamp contains gas, there ensues an ionization thereof and an arc forms across the filament terminals. This arc tends to travel to a position across the points of greatest difference of potential and therefore the arc disposes itself across the main electrodes. Inasmuch as the resistance of the filament is higher than that of the arc gap, during the operation of the lamp, most of the current passes across the arc gap. According to our invention, considered from one standpoint, the electrodes are formed by bending the end portions of refractory metal conductors into unclosed hooks which face each other and are properly spaced apart so as to provide an arc gap. These hooked ends are preferably bent back toward the main portion of the conductors so that the opposed bight portions of the hooked ends are closer together than the extreme end portions of the hooks. A refractory metal filament coil is disposed between the hooked portions so as to be in multiple with the arc gap, and the end portions of said coiled filament surround the aforesaid hooked ends of the conductors. Moreover, the main portion of the filament is out of line of the arc gap. In operation the filament is first caused to glow and then an arc establishes itself gradually between the leg portions of the coiled filament, gradually traveling to the more widely separated end portions which have the greatest difference of potential. Ultimately the arc establishes itself across the main electrodes, and this is facilitated by the fact that these portions are slightly closer together than intermediate portions of the filament.

The above construction provides for the protection of the filament, and the end portions of the filament really act as secondary electrodes. More specifically considered, the filament is com-

posed of two portions, the middle portion and the end portions. In the specific form shown, the middle portion of the filament is of a finer wire than the end portions which constitute the secondary electrodes. Heretofore where other constructions have been employed there has been greater liability of burn-out of the filament at its extremities. In order to have the filament of proper resistance it must necessarily be of comparatively small diameter wire. The result is that when the arc disposes itself across the filament terminals, it is apt to burn out this fine filament. Moreover, the greater the length of the fine filament, the greater the difference between the starting voltage and the operating voltage of the lamp for the same length of arc gap. For these reasons the interposition of secondary electrodes between the main electrodes and the filament serves to improve the performance of the lamp and to increase the power factor which depends upon the relation between the starting and operating voltages. In the Strickland application Serial No. 518,146 is disclosed an arrangement of filament and electrodes in which the electrodes are constituted of coiled refractory metal such as tungsten and in which the ends of the filament extend within the ends of the said electrodes. We prefer to embody that invention in the construction of the filament and secondary electrodes of our lamp and preferably also to have the secondary electrodes extend over and form part of the main electrodes. Various other features and advantages of our invention will appear from the following description of species thereof and from the accompanying drawing.

In the drawing, Fig. 1 is an elevation of a lamp embodying our invention; and Fig. 2 is an elevation partially in section and on an enlarged scale of a portion of the lamp showing more particularly the construction and arrangement of filament and electrodes.

As shown in the drawing, our lamp comprises a bulb 10. Inasmuch as our lamp is particularly adapted to the production of ultra-violet radiation, the bulb 10 is preferably composed of a boro-silicate glass such as those disclosed in Strickland application Serial No. 407,817 above referred to. It is particularly desirable that the light be approximately like sunlight, and for that reason the glass of which the bulb is composed should be such that it will transmit radiation down to about 2900 angstroms but practically no radiation of the very short wave lengths. Of course, if the shorter wave length radiation is desired, a quartz bulb may be used, or if even

less of the ultra-violet is desired, an ordinary glass bulb may be used. The lamp is provided with the usual base 11. The lead wires comprise the outer leads 12-13 which may be of metal ordinarily used such as copper. The inner leads 14-15 should preferably be of a metal of higher melting point, such as molybdenum or tungsten. Seal portions 16-17 are preferably of tungsten, and these are sealed in the hard glass portion of the stem 18. United to the ends of the inner leads 14-15, as by welding, are the tungsten conductors 19-20. The opposite ends of these conductors are bent to constitute the main electrodes 21-22. As shown, the ends of the conductors are hooked and the opposed eight portions are closer together than are the extreme end portions of the hooks as the ends of the hooks are bent back toward the main portions of the conductors. Extending over the electrode portions 21-22 are tungsten coils 23-24. Those portions extending beyond the portions 21-22 constitute secondary or intermediate electrodes and the opposite ends thereof receive the ends of the filament 25 which is of finer tungsten wire. The bulb 10 is filled with an inert gas such as argon, at a pressure of 100 to 125 mm. Hg and the bulb 10 also contains a globule of mercury 26.

In operation, as disclosed in the Strickland application, Serial No. 407,817, hereinbefore referred to, the electric supply circuit includes the transformer with a drooping characteristic, or a suitable ballast, so that sufficient voltage is obtained at the start to cause the filament 25 to glow. This causes an ionization of the argon and mercury vapor with the result that an arc will form across the filament terminals. This arc tends to establish itself across the points of greatest difference of potential and therefore it will transfer itself immediately to a position across the secondary electrodes 23-24, and then it will transfer to a position across the main electrodes 21-22. As shown in the drawing, the gap between the main electrodes is made somewhat less than that between the secondary electrodes so as to insure that the arc will establish itself across the main electrodes inasmuch as the difference in potential between the ends of the secondary electrodes 23-24 is not greatly different than that between the main electrodes 21-22. The provision of the secondary electrode serves to lessen the liability to burn out of the filament 25 at its terminals, inasmuch as there is a quick transference of the arc from across the said terminals. The extension of the coiled secondary electrodes over the portions 21-22 to constitute with said portions the main electrodes serves to resist disintegration of said electrodes by the arc. It will be obvious also that with the construction shown there will be less necessity for a considerable difference between the starting voltage and the operating voltage than if the filament were longer and its terminals further apart.

What we claim as new and desire to secure by Letters Patent of the United States, is:

1. An electric lamp comprising a bulb having therein an atmosphere of readily ionizable gas, a pair of spaced leading-in conductors sealed in a wall of said bulb and projecting into the interior thereof, a pair of spaced metallic main electrodes carried one by each of said leading-in wires and defining therebetween a concentrated arc gap, a filament in said bulb having its middle

portion deflected away from said concentrated arc gap, and a pair of intermediate secondary electrodes of higher current carrying capacity and lower resistance than said filament each adjacent one of said main electrodes but disposed out of the concentrated arc gap therebetween, each of said secondary electrodes being secured at one end to one end of said filament and at its opposite end being electrically connected to the adjacent leading-in conductor. 5

2. An electric lamp comprising a bulb having therein an atmosphere of readily ionizable gas, a pair of spaced leading-in conductors sealed in a wall of said bulb and projecting into the interior thereof, a pair of spaced metallic main electrodes carried one by each of said leading-in wires and defining therebetween a concentrated arc gap, a coiled filament of fine refractory metal wire in said bulb having its middle portion deflected away from said concentrated arc gap, and a pair of intermediate secondary electrodes of coiled coarser refractory metal wire of higher current carrying capacity and lower resistance than said filament each adjacent one of said main electrodes but disposed out of the concentrated arc gap therebetween, each of said secondary electrodes being secured at one end to one end of said filament and at its opposite end being electrically connected to the adjacent leading-in conductor. 10

3. An electric lamp comprising a bulb having therein an atmosphere of readily ionizable gas, a pair of spaced leading-in conductors sealed in a wall of said bulb and projecting into the interior thereof, a pair of spaced metallic main electrodes carried one by each of said leading-in wires and defining therebetween a concentrated arc gap, a coiled filament of fine refractory metal wire in said bulb having its middle portion deflected away from said concentrated arc gap, and a pair of intermediate secondary electrodes of coiled coarser refractory metal wire of higher current carrying capacity and lower resistance than said filament each adjacent one of said main electrodes but disposed out of the concentrated arc gap therebetween, each of said secondary electrodes being secured at one end to one end of said filament and at its opposite end being electrically connected to the adjacent leading-in conductor. 15

4. An electric lamp comprising a bulb having therein an atmosphere of readily ionizable gas, a pair of spaced leading-in conductors sealed in a wall of said bulb and projecting into the interior thereof, a pair of spaced metallic main electrodes carried one by each of said leading-in wires, and a coiled refractory wire filament inside said bulb connected as a shunt across said electrodes and having its middle portion deflected away from the gap between said main electrodes, said filament having one end electrically connected to each of said leading-in conductors adjacent said electrodes but out of the arc gap therebetween, the said end portions of said filament being of higher current carrying capacity and lower resistance than the intermediate portion. 20

5. An electric lamp comprising a bulb having therein an atmosphere of readily ionizable gas, a pair of spaced leading-in conductors sealed in a wall of said bulb and projecting into the interior thereof, a pair of spaced metallic main electrodes

5 carried one by each of said leading-in wires, and a coiled refractory wire filament inside said bulb connected as a shunt across said electrodes and having its middle portion deflected away from the gap between said main electrodes, said filament having one end electrically connected to each of said leading-in conductors adjacent said electrodes but out of the arc gap therebetween, the said end portions of said filament being of 10 coarser wire of higher current carrying capacity and lower resistance than the intermediate portion.

6. An electric lamp comprising a bulb having therein a readily ionizable gas, a pair of spaced 15 leading-in conductors sealed in a wall of said bulb and projecting into the interior thereof and having unclosed hooked ends faced toward each other and spaced apart to form an arc gap, the end of each of said hooks being bent back toward 20 the main portion of the conductor from which it is formed so that the opposed bight portions are closer together than the extreme end portions of said hooks, a coiled refractory wire filament in said bulb having its middle portion deflected 25 away from said arc gap, and a pair of intermediate secondary electrodes of higher current carrying capacity and lower resistance than said filament each adjacent one of said hooked ends but disposed out of the arc gap therebetween, and 30 each of said secondary electrodes being secured at one end to one end of said filament and at its opposite end to the end of the adjacent hook.

7. An electric lamp comprising a bulb having therein a readily ionizable gas, a pair of spaced 35 leading-in conductors sealed in a wall of said bulb and projecting into the interior thereof and having unclosed hooked ends faced toward each

other and spaced apart to form an arc gap, the end of each of said hooks being bent back toward the main portion of the conductor from which it is formed so that the opposed bight portions are closer together than the extreme end 5 portions of said hooks, and a coiled refractory wire filament in said bulb connected as a shunt across said arc gap and having its middle portion deflected away from said arc gap, the end portions of said filament being of higher current 10 carrying capacity and lower resistance than the intermediate portion and being secured at each extremity to the end of one of said hooks.

8. An electric lamp comprising a bulb having therein a readily ionizable gas, a pair of spaced 15 leading-in conductors sealed in a wall of said bulb and projecting into the interior thereof and having unclosed hooked ends faced toward each other and spaced apart to form an arc gap, the end of each of said hooks being bent back toward 20 the main portion of the conductor from which it is formed so that the opposed bight portions are closer together than the extreme end portions of said hooks, and a coiled refractory wire filament 25 in said bulb connected as a shunt across said arc gap and having its middle portion deflected away from said arc gap, the end portions of said filament being of coarser wire of higher current carrying capacity and lower resistance than the intermediate portion, and the said coarser wire end 30 portions each being closely coiled around one of said hooks and extending beyond the end thereof out of the line of the arc gap.
